UNITED STATES PATENT OFFICE.

HERMANN SCHWOERER, OF NEW YORK, N. Y.

ASH TRAY.

Application filed April 7, 1928. Serial No. 262,110.

This invention relates to devices for receiving the ashes from cigars, cigarettes and other tobacco articles and more particularly to an ash tray especially adapted for use by cigarette smokers.

It is well known that the smoke from a continually burning cigarette which has been partially consumed and discarded is very annoying and irritating. It is customary for 10 cigarette smokers to crush such cigarettes to stop the burning but often such precaution is not taken and persons in the immediate neighborhood are subject to considerable annoyance.

15 It is therefore an object of this invention to provide an ash tray which is provided with suitable covered compartment in which burning cigarettes may be discarded.

It is a further object of the present disclosure 20 to provide an ash tray which may be cheaply and readily made from brass or any similar metal.

These and other objects are attained by the 25 novel construction, combination and arrangement of parts hereinafter described and shown in the accompanying drawing, constituting a material part of this disclosure, and in which:—

Figure 1 is a plan view of the ash tray showing 30 the position of the covered compartment.

Figure 2 is a cross-sectional side view of the ash tray and compartment.

Figure 3 is a perspective view of the device showing details of construction.

35 Referring to the drawings, the ash tray is shown to comprise a metal sheet turned to form a lower compartment having a wall 4 and an upper dished surface 5 which is provided with a central aperture and a central flanged portion 6. Integral with the flange 6 are ears 7 adapted to cooperate with ears 9 integral with the cover 8. A pin 10 passes through ears 7 and 9 and, as shown in Figure 3, a spring 14 surrounds the pin 10 to normally hold the cover 8 in a closed position.

In Figures 2 and 3, the cover 8 is shown to have an extension 11 provided with a slot 12, through which passes a pin 15 provided with a head 16. The lower end of the pin passes 50 through a hole 13 in the plates 5 and is provided with a flattened end 18 to prevent its withdrawal from the hole.

Surrounding the pin 17 and positioned between the extension 11 and the surface 5 is a 55 coiled spring 20 which also normally holds

the cover in a position to close the compartment.

The lower part of the compartment is closed by a disc 21 which made be made of metal or any other suitable material.

From the above description, it will be seen that I have provided an ash tray which serves the purpose of the usual ash tray and at the same time provides a compartment into which discarded cigarettes, cigars and the like may be placed. The disc 21 is adapted to be removed from time to time for the purpose of cleaning the device.

It is understood that the foregoing is to be regarded as descriptive and illustrative only since many embodiments may be made without departing from the general scope of the appended claims.

Having thus described my invention, what I claim as new and desire to secure by Letters Patent, is:—

1. An ash tray comprising a hollow sheet metal body having an opening in its lower portion and an aperture in its upper surface, a disc of suitable material adapted to be removably fitted in the opening in the lower portion, central flanges on said upper surface, and a spring controlled cover supported by said flanges and closing the aperture.

2. An ash tray comprising a hollow body having a dish-shaped upper surface, an aperture in said upper surface, an upturned flange on said upper surface surrounding the aperture, a pair of ears on the flange, a cover, a pair of ears integral with the cover, a pin passing through the ears on the cover and the ears on the flange, and a spring surrounding the pin and bearing on the upper surface of the cover to normally hold the cover in a closed position.

3. An ash tray comprising a hollow body having a dish-shaped upper surface, an aperture in said surface, an upturned flange on said surface surrounding the aperture, a cover for said aperture, means for pivotally mounting the cover on the flange, an extension on the cover having a slot therein, a pin passing through the slot and an aperture in the dish-shaped surface and a coiled spring surrounding the pin and bearing against the surface and the extension to normally hold the cover in a closed position.

In witness whereof I have affixed my signature.

HERMANN SCHWOERER.
